(57) **CLAIM**

The ornamental design for a C-shaped clamp for wires and cables, as shown and described.

DESCRIPTION

FIG. 1 is a perspective view of a C-shaped clamp for wires and cables, showing my new design;
FIG. 2 is a right side elevation view thereof, the left side elevation view being a mirror image thereof;
FIG. 3 is a front elevational view thereof;
FIG. 4 is a rear elevational view thereof; and,
FIG. 5 is a top plan view thereof, the bottom plan view being a mirror image thereof.
